United States Patent Office.

EPHRAIM ROMANS, OF LA PORTE, INDIANA.

Letters Patent No. 70,620, dated November 5, 1867.

IMPROVED BAG-FASTENER.

The Schedule referred to in these Letters Patent and making part of the same.

TO ALL WHOM IT MAY CONCERN:

Be it known that I, EPHRAIM ROMANS, of La Porte, Indiana, have invented a new and useful Machine for Fastening Bags; and I do hereby declare that the following is a full, clear, and exact description of the construction and operation of the same, reference being had to the annexed drawings, making a part of this specification, in which—

Figure 1 is a top view of the fastener, and

Figure 2 is a perspective view of the same with the string attached.

The nature of my invention consists in providing a convenient, easy, and secure method of fastening and unfastening bags, by means of a string attached by a peculiar-shaped buckle or metal plate.

To enable others skilled in the art to make and use my invention, I will proceed to describe its construction and operation.

a is a light but substantial wire or metal frame, upon which is attached, at *c*, the tongue or plate *b*, with the notch or bite *e* for holding the cord *f*, and also with the notches *h h*, around which to fasten the end of the cord *f*. The cord *f* being securely fastened at *h h*, is passed around the bag to be secured, and then being drawn tightly, until the knot *i* of the cord passes through the frame *a*, and is caught and held by the bite *e* in the plate *b*.

What I claim as my invention, and desire to secure by Letters Patent, is—

The combination of the frame *a*, plate *b*, and cord *f*, substantially as and for the purpose described.

EPHRAIM ROMANS.
